(57) **CLAIM**

The ornamental design for an electronic device, as shown and described.

DESCRIPTION

FIG. 1 is a front perspective view of an electronic device showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is another front perspective view of the electronic device of FIG. 1 shown in an alternate configuration;

FIG. 9 is another front perspective view of the electronic device of FIG. 1 shown in an alternate configuration;

FIG. 10 is another front perspective view of the electronic device of FIG. 1 shown in an alternate configuration; and,

FIG. 11 is a front perspective view of FIG. 1 shown in a different state of use.

The dashed broken lines illustrate portions of the electronic device that form no part of the claimed design. The other dashed broken lines in FIG. 11 illustrate environmental subject matter that forms no part of the claimed design. The dot-dash broken lines in FIGS. 1-5 and 8-11 define the boundaries of the claimed design and form no part thereof. The perspective views in FIGS. 8 to 10 illustrate alternate configurations in which the display progressively widens from FIG. 8 to FIG. 9 to FIG. 10. The appearance of the electronic device sequentially transitions between the images shown in FIGS. 8 to 10. The process or period in which one image transitions to another image forms no part of the claimed design.
